DESIGN FOR A PERFUME CONTAINER

William Appleby, Brooklyn, N. Y.

Application February 14, 1948, Serial No. 144,505

Term of patent 3½ years

(Cl. D86—10)

To all whom it may concern:

Be it known that I, William Appleby, a citizen of the United States, residing at 971 East 26th Street, Brooklyn, in the county of Kings and State of New York, have invented a new, original, and ornamental Design for Perfume Containers, of which the following is a specification, reference being had to the accompanying drawing, forming part thereof.

Fig. 1 is a top plan view of a perfume container, showing my new design;

Fig. 2 is a front elevation of the embodiment shown in Fig. 1, and

Fig. 3 is a bottom plan view of same.

I claim:

The ornamental design for a perfume container, substantially as shown.

WILLIAM APPLEBY.
